UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

SECTIONAL-JUSTIFICATION MECHANISM FOR COMPOSING-MACHINES.

1,283,624.

Specification of Letters Patent.

Patented Nov. 5, 1918.

Application filed November 1, 1916. Serial No. 128,951.

To all whom it may concern:

Be it known that we, JOHN SELLERS BANCROFT and MAURITZ C. INDAHL, citizens of the United States, and residents of Philadelphia, county of Philadelphia, State of Pennsylvania, have invented certain new and useful Improvements in Sectional-Justification Mechanism for Composing-Machines; and we do hereby declare the following to be a full, clear, and exact description of the same, reference being had to the accompanying drawings, forming a part of this specification.

This invention relates to keyboard composing machines for producing record strips containing signals representing characters and spaces which will form justified lines of type, and has for its principal object to provide mechanism for indicating justification for sectional portions of lines whereby a record strip is producible in which there are signals for justification within the line measure as well as at the end thereof. Such a mechanism is especially valuable in connection with the composition of tabular matter and the like, in which each line is made up of sections the composition of which must each be located at a certain definite point in the measure. More specifically, the object of this invention is to provide mechanism so arranged with respect to the line measuring mechanism and the justification indicating mechanism of a suitable composing machine that these last mentioned mechanisms may be operatively connected, when desired, to the end that within its limits the justification indicating scale will indicate justification necessary due to the movement of the line measuring mechanism after the connection has been established. Other objects of this invention will be particularly pointed out or will otherwise appear in connection with the following description of the embodiment of the invention shown in the accompanying drawings, in which—

Figure 1 is a side elevation of a keyboard composing machine provided with the device of the present invention, certain parts being broken away and in section.

Fig. 2 is a front elevation of the mechanism of Fig. 1.

Fig. 3 is an enlarged plan view of a part of the mechanism of Figs. 1 and 2, the justification indicator scale being removed.

Fig. 4 is a vertical section through the pin lock in locked position, the units wheel pawl being shown in dotted lines out of contact with the units wheel.

Fig. 5 is a vertical cross section substantially through the units wheel shaft.

Fig. 6 is a horizontal section through the justification indicator motor.

Fig. 7 is a section substantially on the line 7—7 of Fig. 6, and

Fig. 8 is a perspective of the pin lock and its actuating mechanism and the tilting shaft, the latter in its down position, but not advanced to permit of its being locked by the pin lock.

The drawings illustrate the invention as applied to an improved keyboard composing machine of the general type shown in United States Patent No. 944,405 to Bancroft and Indahl, dated December 28th, 1909. It is not necessary to describe this machine in detail, it being sufficient for present purposes to designate and identify some of the parts of such machine shown in the accompanying drawings, especially those which are operatively or otherwise involved with the mechanism of the present invention, for example, the keys 180 operating through pneumatic means certain of the punch bar levers 17 and punch bars 15; the stop bars 13 (Fig. 2) on the outer ends of levers each operated from a dimensioning punch bar 15 through a lever 20 and a vertically movable bar 40; the units rack 11 slidable in the units rack carrier 42 operated from the universal bar 19; the units wheel 7 driven by air under pressure in the motor cylinder 4 acting against the piston 4¹, (Fig. 5) which piston carries the motor rack 6 meshing with the pinion 6¹ secured to the units wheel shaft; the line scale pointer 14¹ carried by the line scale rack 14 in mesh with the line scale pinion 7¹, also secured to the units wheel shaft; the units wheel retaining pawl 12 capable of having its teeth moved out of mesh with teeth of the units wheel by pivotal movement of the lever 74 acting against the link 61 and normally operated by the admission of air under pressure to the tripping motor 79 (Fig. 3) connected with the lever 74 by the arm 78, shaft 77, arm 76 and link 75, such operation being accompanied by the returning or restoring of the line measuring mechanism to its initial position; the justification in-

100
105

dicator drum 8 and the justification pointer 14^a carried by the vertical ratchet bar 85 driven upwardly by pawl and ratchet means and allowed to fall to initial position by the 5 action of the trip 92 for said means, said trip being operated from the arm 93 (Fig. 4) secured to the shaft 77.

While the sectional justification mechanism of this invention may be used in connection with the machine of the above mentioned patent in which the justification indicating means is normally connected with the line measuring mechanism and caused to operate within the justification area in 10 proximity to the end of the line being composed, by the manual depression of a special key, we have shown in the present drawings an improved machine in which the justification indicating means is normally connected 15 automatically with the line measuring mechanism within such area. Such an automatically operative mechanism causes the justification indicating means to follow up the movements of the line measuring mechanism 20 and is shown, for example, in United States Patent No. 1,149,176 to Bancroft and Indahl, dated August 10th, 1916, and this part of the present mechanism need not therefore be described in detail except as it differs 25 from the mechanism of said last mentioned patent. This mechanism comprises the abutment slide 9^a, (Figs. 5 and 7) moved by the motor piston 4¹, and having a vertical extension 15^a one side of which is in contact 30 with the piston rod 14^a, (Fig. 6) of the piston 13^a in cylinder 12^a, such piston and cylinder constituting an abutment slide return motor, and the other side of which extension 15^a is in engagement with the rod 35 19^a, provided with a shoulder 20^a, co-operating with which is an adjusting sleeve 21^a, surrounding the rod 19^a and screw threaded into the gaging member 9 which surrounds both the rods 14^a and 19^a. This gaging 40 member 9 is slidable in the cylinder 12^a and bearing 11^a and is provided with a slot opening 16^a through which projects the extension 15^a of the abutment slide 9^a. In the present drawings the slot opening 16^a is 45 shown to be of greater size than in the last mentioned patent, the stop 22^a, (Fig. 3) for the rod 19^a is shown adjustable in its holding frame and other minor alterations have been made to give the gaging member 9 a 50 wider range of movement. The importance of these slight changes will be explained hereinafter in connection with the description of the operation of the invention.

The present drawings also show a pneumatic motor which may be used, if desired, for operating the justification indicator scale instead of the spring motor of the patent. This pneumatic motor comprises the cylinder 25^a and piston 24^a therein, said 55 piston being provided with a piston rod 23^a

having its end 26^a remote from the piston, guided in a bearing 27^a. The rod 23^a is provided with rack teeth with which mesh the teeth of a pinion, the diametrically opposite side of which pinion engages with the rack 70 teeth of the gaging member 9. This pinion is a part of the gearing 10^a for transmitting motion of the racks to the justification indicating scale or drum. The motor 24^a, 25^a is supplied with air under pressure through 75 the pipe 28^a which connects with the pipe 17^a leading to the abutment slide return motor (Fig. 3).

In this invention the connecting means between the line measuring mechanism and the justification indicating means is independent of the normal connecting means operative only within the justification area and is in the form of a shaft 50 provided with pinions 51 and 52 adapted to mesh 80 respectively with the gear 53 connected with the said scale and with the units wheel 7 of the line measuring mechanism. The gear 53 is located axially of and below the justification indicating scale 8 and is secured to 85 the rotatable support for said scale so that the scale and this gear will turn together. The pinions 51 and 52 are identical in shape and size and when meshed with the units wheel and the gear 53 the turning of the 90 units wheel a given number of units will result in the operation of the drum correspondingly. In other words, the same operative relation that exists between the units wheel and the indicator drum while the line 95 measuring mechanism is traversing the justification area at the end of the line may be brought into existence at any point in the line, for example, before the said area is reached, merely by connecting the gear 100 105 53 and the units wheel 7 by means of the shaft 50 and its pinions 51 and 52.

Normally these pinions are in inoperative or unconnected position (Fig. 1) so that they may not interfere with the ordinary 110 composition of a line but the connection may be made manually at any point in the line being composed. One arrangement for accomplishing this is as follows:

The shaft 50 is mounted in a pivoted member 54 having a lateral projection 55 by which said member is pivotally mounted in the bearing 56 in the machine frame, the axis of said bearing being transverse to the shaft and extending between the shaft pinions so 115 that when the shaft is tilted upward upon this projection 55 as a pivot as shown in Fig. 1, the pinions are out of mesh with the gear 53 and the units wheel. This normal position is maintained by a compression 120 spring 57 the upper end of which is located in a socket 58 in the bearing 54 and the lower end of which rests upon the ear 59 of the stationary bracket 60. Depression of the outer end of the sheet 50, however, as by 125 130

pressing down upon the knurled head or handle 61¹ thereon, against the pressure of spring 57 will move the pinions 51 and 52 into mesh with the gear 53 and the units wheel 7 respectively, as shown in Fig. 5.

The bracket 60 is provided with a projecting lip 62 which is adapted to enter a recess in the knurled head 61¹ when the shaft 50 has been first tilted to horizontal or 10 meshed position and then advanced longitudinally, the parts, after such movement being in the position shown in Fig. 5. It will be readily seen that the lip 62 serves to lock the shaft 50 in horizontal position from 15 which it can only be removed by first retracting or withdrawing the shaft longitudinally and then allowing the spring 57 to tilt it upwardly to the position of Fig. 1.

Located a short distance from and at one 20 side of the knurled head 61¹ is a finger lever 63 projecting from a pivoted boss 64, mounted upon a pin 65 fixed to and projecting from the casting for the stop 22^a above referred to. The boss is provided 25 with a lever arm 66 which normally rests against the tripping lever 74 (Fig. 4) in the normal position of the latter and with a lever arm 67 projecting upwardly from the boss 64 and normally resting against the 30 locking pin 68 to be presently described. The boss may also be provided with a third, downwardly extending lever arm 69 normally resting against the side of the latch 101 normally tripped by the pin 103 (Figs. 35 1 and 3) on the line scale rack to effect the operation of a signal light, such as an illuminating device for the justification scale.

The locking pin 68 extends through the 40 pivotal axis of the bearing 56, its inner end being reduced in diameter whereby a shoulder is formed against which the spring 70 (Fig. 4) exerts pressure tending to maintain the outer end of the pin in contact with the lever arm 67. The opposite end of the 45 spring reacts against a reduced portion 71 of the projection 55 which is suitably bored to accommodate the pin. The inner end of the pin is adapted, when the pin is moved by the lever arm 67 against the force of the spring, 50 to enter a groove 72 in the tilting shaft 50 when said shaft is in the advanced horizontal or connected position. The shaft is thus locked by the pin so as to prevent withdrawal of the shaft whereby tilting of the 55 shaft is prevented due to the engagement of the locking lip 62.

The pin is caused to enter the groove 72 by depression of the finger lever 63 which rotates the boss 64 and operates the arm 67 60 against the outer end of the pin. The depression of the finger lever also causes the end of lever arm 69 to operate the latch 101 and that of lever arm 66 to depress the tripping lever 74 sufficiently to result in the unmeshing of the locking pawl 12 from the

teeth of the units wheel. The depression of the tripping lever is limited by the engagement of the shoulder 73 on the pin lock 68 with the end of extension 55 and is insufficient to cause the restoring of the justification pointer 14^x; that is to say, the depression of the lever 74 under the lever arm 66 raises the opposite end of lever 74 and with it the link 75 so as to cause an upward rocking of the crank arm 76, the latter rocking the shaft 77 and the arm 93 and moving the trip 92 for the pawl and ratchet device which device raises and maintains in raised condition the ratchet bar 85 supporting the pointer 14^x, but the present movement of these parts is insufficient in extent to cause the trip 92 to act. The complete movement of these parts resulting in the fall of the pointer 14^x to its normal position is only accomplished by the operation of the usual key to admit air pressure to the tripping motor 79.

The inner end of the projection 55 of the pivoted member 54, may be provided with an opening into which may extend, as shown, the shank of a brake member 80, said member being itself provided with an axial aperture through which the pin 68 extends. The brake member is provided on its inner end with a shoe 81 which engages at all times and operates upon the shaft 50, being pressed against said shaft by a spring 82 engaging at one end with the end of the brake shank and at the other end with the reduced portion 71 of the projection 55. The brake 90 member, while not a necessary element of the structure, is useful to prevent or resist the accidental turning of the units wheel by the motor 4 at a time for instance when the pawl 10 12 is removed from the units wheel and the operator partially releases his grasp of the knurled head 61¹ preliminarily to obtaining a new grasp thereof.

A dial 83, (Figs. 2 and 3) and a co-operating pointer 84 secured to a shaft 86 having 110 bearings in a bracket 87 secured to the machine frame in the neighborhood of the justification indicating motor (said shaft being geared to the units wheel by a pinion 88 (Fig. 3) carried on its inner end) may be provided as a multiplying indicator for indicating clearly subdivisions of the line scale graduations, the latter usually representing ems. Preferably the dial indicator is constructed so that the pointer makes a complete revolution for an ein-movement of the line scale pointer 14^x, and the dial is divided into units, each unit being an eighteenth part of an em.

As shown in Figs. 2 and 3 a bolt 89 is singularly set in the machine frame with its head flanged to contact with the lower side of the end of the releasing pawl 12, the other, upper end of the bolt being screwthreaded and provided with an adjusting nut 90. 125 130

This arrangement has for its purpose the accurate adjustment of the teeth of the pawl 12 with relation to the teeth of the units wheel.

- 5 The production of tabular matter or other matter requiring sectional justification, is accomplished preferably in the following manner: The composition of a line section having progressed until the line scale pointer 14¹ is within the justification area measured from the point of beginning the next section and the justification pointer 14^x having moved upwardly in the usual manner one 10 step for each justification space in the composition, the knurled head 61¹ is grasped between the thumb and first finger of the right hand and pressed downwardly from its normal position shown in Figs. 1, 2 and 3. The shaft 50 and its member 54 are thus 15 tilted on the projection 55 as a pivot to horizontal position and the pinions 51 and 52 become meshed with the gear 53 and the units wheel 7 respectively. The tilting movement is arrested by the contact of the shaft 50 20 with the bracket 60 and the parts will have the position shown in Fig. 8. The shaft 50 is now pushed in or advanced until the recess in the knurled head 61¹ engages with the lip 62. In this position, shown in Fig. 5, the 25 shaft 50 is locked from tilting upward by the lip 62, the gears 51, 53 and 52, 7 are still in meshed relation and the groove 72 is opposite the end of the pin 68. The little finger or other suitable finger of the right 30 hand is now caused to depress the lever 63 without the grasp of the knurled head between the thumb and first finger being released, such depression resulting in movement of the pin 68 into the groove 72. 35 40 through the medium of the lever arm 67 and in the unmeshing of the units wheel retaining pawl 12 from the teeth of the units wheel, this last result taking place through the action of the lever arm 66 upon the link 45 61 through the pivoted lever 74 and being timed to occur after the pin 68 has entered the groove 72. When the boss 64 is provided with a lever arm 69, the depression of the finger lever 63 will also result in the 50 tripping of the latch 101. The parts are now in the position shown in Fig. 4 and the shaft 50 is not only locked from upward tilting by the lip 62 but it is also locked from withdrawal horizontally by the pin lock 68. 55 When the latch 101 is tripped by depressing the finger lever 63, as well as when it is tripped by the pin 103 on the line scale rack 14, an electric circuit is closed by the releasing of the spring switch 95 diagrammatically shown in Fig. 3, thus lighting the 60 signal light 96 located in position to illuminate the justification scale. The light is extinguished by reversely operating the switch 95, this being preferably accomplished by 65 the pneumatic motor 97 connected with the

switch and operated by air under pressure in the pipe 98, the latter being connected with the cylinder of tripping motor 79 previously referred to, which tripping motor receives air under pressure in connection with the 70 restoring of the line measuring mechanism to its original position.

The knurled head 61¹ is now rotated until the area to be justified is passed over by the line scale pointer 14¹ and the latter rests at 75 the graduation at which the composition of the next section is to begin. This positioning may be very accurately made by reference to the dial indicator. Such rotation of the knurled head not only moves the 80 line scale pointer through the gearing 52, 7, 7¹ and rack 14 but it also moves the justification indicating drum 8 correspondingly through the gears 51, 53 and at the end of the movement it is only necessary to read 85 the justification indications as pointed out by the indicator 14^x and then justify in the usual manner and restore the justification pointer 14^x to normal position by the operation of the trip motor 79, the line measuring 90 devices being held from movement during the restoring operation by holding the knurled head 61¹ against rotation. After justification and with the line scale pointer 14¹ remaining positioned at the graduation 95 at which the next section of composition is to begin, the pin lock 68 is released and the pawl 12 placed in mesh with the units wheel by releasing the finger lever 63, after which the knurled head and the shaft 50 can be 100 manually withdrawn and restored to normal position through the action of spring 57. It will be readily seen that in positioning the shaft 50 for operation, said shaft is locked by the pin lock 68 before the pawl 105 12 is removed from the units wheel and that in restoring the shaft 50 to its normal tilted position the pawl 12 is meshed with the units wheel before the shaft 50 is unlocked from the pin 68; at any given time, 110 therefore, at least one of the two locking means is in locked position. The composition of the next section is now proceeded with and unless it is the last section, justified in the same way. The justification of 115 the last section of the line composed of a full line is indicated in the usual manner by the automatic action of the justification indicator mechanism of the machine shown or the manual operation of the machine shown 120 in Patent #944,405, the mechanism of the present invention being made use of ordinarily only at intermediate points of the measure. The proper justifying keys are struck in the manner commonly employed for double justification whereby the proper signal is given so that the galley rod of the casting machine will be tripped 125 and the line delivered to the galley.

When the justification indicating drum 300

is rotated, as explained above, from the knurled head 61^a, there is also produced a movement of the normal justification indicating mechanism because the latter is at all 5 times connected with the drum through the gearing 10^a. This gearing transmits motion to the rack of the members 9 and 23^a and these members and their associated parts must, therefore, be free to move an 10 amount corresponding with a complete revolution of the justification indicating drum in either direction from its normal position, this being necessary because the normal justification indicating devices turn the drum 15 in one direction while the manual sectional operation is usually in the opposite direction and the range of movement for each is necessarily one revolution of the drum. This range is provided for as shown by providing sufficiently long cylinders, bearings, and rack portions for the members 23^a and 9, providing a sufficiently long slot opening 16^a (Fig. 6) in the gaging member 9 and providing a stop 22^a for the rod 19^a of 20 smaller diameter than the rod so that the member 9 may slide over said stop in the extreme of its motion in one direction. The stop 22^a is made adjustable and is set 25 by turning it in its support and then clamping it by the nut threaded upon it, so that when the rod 19^a rests against the end of the stop the justifying drum will be at zero position. The proper relation between the gaging member 9 and the abutment slide 30 35 9^a is adjusted in the usual manner by manipulating the adjusting sleeve 21^a.

We claim:—

1. A typographic composing machine embodying in combination line measuring mechanism, justification indicating means and means adapted to be positioned manually to connect said measuring mechanism and said indicating means whereby manual operation of said measuring mechanism 40 45 produces a corresponding operation of said indicating means.

2. A typographic composing machine embodying in combination line measuring mechanism, justification indicating means and means normally unconnected with but adapted at any point in the line being composed to be connected with said line measuring mechanism and said indicating means, said connecting means being manually movable to connected position and being manually operative when in such position to cause operation of the line measuring mechanism and the indicating means.

3. A typographic composing machine embodying in combination line measuring mechanism, justification indicating means and means normally unconnected with but adapted at any point in the line being composed to be connected with said line measuring mechanism and said indicating means,

said connecting means including a handle for the manual operation of said line measuring mechanism and said indicating means.

4. A typographic composing machine embodying in combination line measuring mechanism, justification indicating means and means normally unconnected with but adapted at any point in the line being composed to be connected with said line measuring mechanism and said indicating means, said connecting means comprising a shaft, gears secured thereto and a handle for operating the shaft.

5. A typographic composing machine embodying in combination line measuring mechanism including a units wheel, justification indicating means including an indicator scale and a rotatable support therefor, and means normally unconnected with but adapted at any point in the line being composed to be connected with said line measuring mechanism and said justification indicating means, said connecting means comprising a shaft, gearing thereon for directly connecting said units wheel and said indicator scale support and a handle for operating the shaft.

6. A typographic composing machine embodying in combination line measuring mechanism including a units wheel, justification indicating means including an indicator scale and a rotatable support therefor, a gear secured to said support, a shaft, gears secured to said shaft for meshing with said support gear and said units wheel respectively and a handle for operating said shaft.

7. A typographic composing machine embodying in combination line measuring mechanism including a units wheel, justification indicating means including an indicator scale and a rotatable support therefor, a gear secured to said support, a shaft tiltable on an axis transverse to the shaft, gears secured to said shaft for meshing with said support gear and said units wheel respectively, means for normally maintaining said shaft in tilted position whereby the gears thereon are normally unmeshed with said support gear and said units wheel and a handle for moving said shaft into position in which the said gears are in mesh and for turning the shaft.

8. A typographic composing machine embodying in combination line measuring mechanism, justification indicating means, means normally unconnected with but adapted at any point in the line being composed to be connected with said line measuring mechanism and said indicating means, said connecting means being manually movable to connected position and being manually operative when in such position to cause operation of the line measuring mechanism and the indicating means, and means for

locking said connecting means in the connected position thereof.

9. A typographic composing machine embodying in combination line measuring mechanism including locking means therefor, justification indicating means, means normally unconnected with but adapted at any point in the line being composed to be connected with said line measuring mechanism

5 10 and said justification indicating means, means for locking said connecting means in connected position and means for operating said two locking means whereby at any given time at least one of them is in locked 15 position.

10. A typographic composing machine embodying in combination line measuring mechanism, a locking pawl associated therewith, justification indicating means, means

20 normally unconnected with but adapted at any point in the line being composed to be connected with said line measuring mechanism and said justification indicating means, a handle secured to said connecting means

25 whereby when in connected position the line measuring mechanism and the justification indicating means may be operated by said connecting means, manual means for unlocking the locking pawl from the line measuring mechanism to permit of such 30 operation and manual means for locking the connecting means in connected position and preventing the unlocking of the pawl until after the said locking of the connecting 35 means has been accomplished.

11. A typographic composing machine embodying in combination line measuring mechanism, justification indicating means, mechanism for connecting said line measuring mechanism and said indicating means in proximity to the end of the line being composed and manually operative means for connecting said line measuring mechanism and said indicating means at any point 45 in the line being composed.

12. A typographic composing machine embodying in combination line measuring mechanism, justification indicating means, mechanism for connecting said line measuring mechanism and said indicating means in proximity to the end of the line being composed and means independent of said connecting mechanism for connecting said line measuring mechanism and said indicating means at any point in the line being composed.

13. A typographic composing machine embodying in combination line measuring mechanism, justification indicating means 60 including a justification pointer, means for operating the said pointer and a justification indicator scale, mechanism for connecting said line measuring mechanism and said indicator scale in proximity to the end of the 65 line being composed and means independent

of said connecting mechanism for connecting said line measuring mechanism and said indicator scale at any point in the line being composed.

14. A typographic composing machine 70 embodying in combination line measuring mechanism, justification indicating means, mechanism for connecting said line measuring mechanism and said indicating means in proximity to the end of the line being composed and means normally unconnected with 75 but adapted at any point in the line being composed to be connected with said line measuring mechanism and said indicating means, said last mentioned connecting means being 80 manually movable to connected position and being manually operative when in such position to cause operation of the line measuring mechanism and the indicating means.

15. A typographic composing machine 85 embodying in combination line measuring mechanism, justification indicating means, mechanism for connecting said line measuring mechanism and said indicating means in proximity to the end of the line being composed and means normally unconnected with 90 but adapted at any point in the line being composed to be connected with said line measuring mechanism and said indicating means, said last mentioned connecting means 95 including a handle for the manual operation of the line measuring mechanism and the indicating means.

16. A typographic composing machine embodying in combination line measuring 100 mechanism, justification indicating means, mechanism for connecting said line measuring mechanism and said indicating means in proximity to the end of the line being composed and means normally unconnected with 105 but adapted at any point in the line being composed to be connected with said line measuring mechanism and said indicating means, said last mentioned connecting means comprising a shaft, gears secured thereto and 110 a handle for operating the shaft.

17. A typographic composing machine embodying in combination line measuring mechanism including a units wheel, justification indicating means including an indicator scale and rotatable support therefor, mechanism for connecting said line measuring mechanism and said indicating means in proximity to the end of the line being composed and means normally unconnected with 115 120 but adapted at any point in the line being composed to be connected with said line measuring mechanism and said indicating means, said last mentioned connecting means comprising a shaft, gearing thereon for directly connecting said units wheel and said indicator scale support and a handle for operating the shaft.

18. A typographic composing machine embodying in combination line measuring 125 130

mechanism including a units wheel, justification indicating means including an indicator scale and a rotatable support therefor, a gear secured to said support, mechanism for connecting said line measuring mechanism and said indicating means in proximity to the end of the line being composed, a shaft, gears secured to said shaft for meshing with said support gear and said units wheel respectively and a handle for operating said shaft.

19. A typographic composing machine embodying in combination line measuring mechanism including a units wheel, justification indicating means including an indicator scale and a rotatable support therefor, a gear secured to said support, mechanism for connecting said line measuring mechanism and said indicating means in proximity to the end of the line being composed, a shaft tilttable on an axis transverse to said shaft, gears secured to said shaft for meshing with said support gear and said units wheel respectively, means for normally maintaining said shaft in tilted position whereby the gears thereon are normally unmeshed with said support gear and said units wheel and a handle for moving said shaft in position in which said gears are in mesh and for turning said shaft.

20. A typographic composing machine embodying in combination line measuring mechanism, justification indicating means, mechanism for automatically connecting said line measuring mechanism and said indicating means in proximity to the end of the line being composed and means normally unconnected with but adapted at any point in the line being composed to be manually connected with said line measuring mechanism and said indicating means.

21. A typographic composing machine embodying in combination line measuring mechanism, justification indicating means, mechanism for automatically connecting said line measuring mechanism and said indicating means in proximity to the end of the line being composed and for causing the latter to operate by following up the movements of the former, and manually operative means for connecting and operating said line measuring mechanism and said indicating means at any point in the line being composed.

22. A typographic composing machine embodying in combination line measuring mechanism, justification indicating means, mechanism for connecting said line measuring mechanism and said indicating means in proximity to the end of the line being composed, means normally unconnected with but adapted at any point in the line being composed to be connected with said line measuring mechanism and said indicating means and means for locking said last mentioned

connecting means in the connected position thereof.

23. A typographic composing machine embodying in combination line measuring mechanism including locking means therefor, justification indicating means, mechanism for connecting said line measuring mechanism and said indicating means in proximity to the end of the line being composed, means normally unconnected with but adapted at any point in the line being composed to be connected with said line measuring mechanism and said indicating means, means for locking said last mentioned connecting means in connected position and means for operating said two locking means whereby at any given time at least one of them is in locked position.

24. A typographic composing machine embodying in combination line measuring mechanism, justification indicating means, manually operative means connecting said line measuring mechanism and said indicating means whereby said measuring mechanism and said indicating means are capable of being operated manually and a brake operating upon said connecting means.

25. A typographic composing machine embodying in combination line measuring mechanism, justification indicating means, means normally unconnected with but adapted at any point in the line being composed to be connected with said line measuring mechanism and said indicating means, said connecting means being manually movable to connected position and being manually operative when in such position to cause operation of the line measuring mechanism and the indicating means, and a brake for resisting said operation of the connecting means when in connected position.

26. A typographic composing machine embodying in combination line measuring mechanism including a units wheel, justification indicating means including an indicator scale and a rotatable support therefor, a gear secured to said support, a shaft tilttable on an axis transverse to said shaft, a brake operating upon said shaft in proximity to said axis, gears secured to said shaft for meshing with said support gear and said units wheel respectively, means for normally maintaining said shaft in tilted position whereby the gears thereon are normally unmeshed with said support gear and said units wheel, and a handle for moving said shaft in position in which the said gears are in mesh and for turning the shaft, said brake resisting said turning operation.

27. A typographic composing machine embodying in combination line measuring mechanism including locking means therefor, justification indicating means, means normally unconnected with but adapted at any point in the line being composed to be con-

nnected with said line measuring mechanism and said indicating means, means for locking said connecting means in connected position, means for operating said two locking means whereby at any given time at least one of them is in locked position and a brake for said connecting means for resisting the operation thereof when the locking means for the line measuring mechanism is in unlocked position.

28. A typographic composing machine embodying in combination line measuring mechanism, justification indicating means, means normally unconnected with but adapted at any point in the line being composed to be connected with said line measuring mechanism and said indicating means, said connecting means being manually movable to connected position and being manually operative when in such position to cause operation of the line measuring mechanism and the indicating means, means for locking said connecting means in connected position, a signal light and means for operating said signal light at the time of locking said connecting means.

29. A typographic composing machine embodying in combination line measuring mech-

anism, justification indicating means, mechanism for connecting said line measuring mechanism and said indicating means in proximity to the end of the line being composed, a signal light, means associated with said line measuring mechanism for operating said signal light in proximity to the end of the line being composed, manually operative means for connecting said line measuring mechanism and said indicating means at any point in the line being composed and means associated with said connecting means for operating said signal light.

30. A typographic composing machine embodying in combination line measuring mechanism including a line scale, a multiplying indicator connected with said line measuring mechanism, justification indicating means, and manually operative means connecting said line measuring mechanism and said indicating means for operating the same, the extent of operation of said line measuring mechanism and said indicating means being indicated by the multiplying indicator in subdivisions of the graduations of the line scale.
